UNITED STATES PATENT OFFICE.

MAX HACKLÄNDER, OF NEVIGES, GERMANY.

PADLOCK.

1,407,267.

Specification of Letters Patent. Patented Feb. 21, 1922.

Application filed November 8, 1920. Serial No. 422,685.

To all whom it may concern:

Be it known that I, MAX HACKLÄNDER, citizen of the German Republic, residing at Neviges, Rhineland, Germany, have invented 5 new and useful Improvements in Padlocks (for which I have filed applications in Germany, Sept. 25, 1919, and in Austria, Apr. 9, 1920,) of which the following is a specification.

10 The invention relates to padlocks in which the pivot of the shackle is automatically raised or lowered when the key is turned in one direction or the opposite.

The object of the invention is to arrange 15 the pivot of the shackle on a disk which is coupled with the turnable central portion of a round flat guiding member or guide-cylinder provided with the tumblers. By this arrangement an exceedingly high degree of 20 security is attained without the provision of a bolt, because the disk which carries the shackle can only be turned after the pin tumblers have been positioned in the most accurate manner, and this, of course, can 25 only be accomplished by using the proper key.

A specially high degree of security can be attained by pivoting the link between a pair 30 of disks and by arranging a separate guide cylinder with pin tumblers both at the front and the back of the said pair of disks.

A constructional form of a padlock according to the invention is shown in the drawing in which

35 Fig. 1 is front view of the lock when closed,

Fig. 2 shows the interior of the lock with the shell removed. In this figure the pin tumblers of the guide cylinder arranged in 40 front of the pair of disks are so positioned as to allow the lock to be opened and the turnable central portion of the cylinder, together with the pair of disks, are turned through approximately an eighth of a revolution.

45 Fig. 3 shows a similar view of the internal parts, but with the shackle fully opened.

Fig. 4 shows the interior of the lock after 50 the guide cylinder provided with pin tum-

blers, and arranged in front of the said pair of disks, has been removed.

Fig. 5 is a cross section of the lock on a line through its centre.

Fig. 6 shows a side view and a cross section of the key.

Fig. 7 is a front view of the pair of disks carrying the pivot of the shackle.

Fig. 8 is a side view of the arrangement shown in Fig. 7.

Fig. 9 is a front view of the central portion of the guide-cylinders provided with the tumblers.

Fig. 10 is a plan of the central portion shown in Fig. 9.

Fig. 11 is a front view of one of the guide-cylinders provided with the tumblers.

Fig. 12 is a plan of the guide-cylinder shown in Fig. 11.

Fig. 13 shows the interior of the lock with 70 the shell removed. In this figure the guide-cylinder arranged in front of the pair of disks carrying the pivot of the shackle is partly shown in section.

The shackle *b* is pivoted on a pin *a* that 75 is fixed between the two disks *c*, *c* rigidly fixed to each other. Arranged at the front and rear of the pair of disks *c*, *c* are round flat guiding members or guide-cylinders *d*, *d* each having a central portion *e* that is turnable in a known manner, whilst the outer annular portion is fixed in the shell of the lock or on its sheet metal base.

Arranged in the pair of disks *c*, *c* are four pins *f* whose projecting front and rear ends 85 are fixed in the front and back guide cylinders *d* so that the pair of disks *c*, *c* can only be turned together with the central parts of the two guide cylinders *d*, and a turning of the pair of disks can only take place after 90 the pin tumblers of the two guide cylinders have been most accurately positioned.

When the pin tumblers have been properly positioned by the insertion of the correct key *g* furnished with four bits, the key 95 when turned will carry around the two central portions *e*, *e* and the pair of disks *c*, *c* attached thereto by the pins *f*, whereby the semi-circular shackle will first be lifted until its front limb is raised clear of the rim 100

of the lock case (see Fig. 2), and subsequently, when the key is turned further around and the shackle strikes against the edge of the aperture in the rim, it will be 5 swung back into its fully opened position (Fig. 3). A backward turn of the key will cause the shackle *b* to swing round in the opposite direction.

By increasing the number of pin tumblers 10 in the guide cylinders the degree of security of this type of lock may be further enhanced.

I claim:

1. In a padlock; a turnable disk; a shackle pivoted on the said disk; a guide cylinder 15 comprising a fixed portion and a central rotary portion coupled with the said disk; and tumblers cooperating with the fixed and rotary portions of the said guide cylinder

and adapted to prevent the movement of the rotary portion and the turnable disk except 20 when operated by a proper key.

2. In a padlock; a pair of turnable disks; a shackle pivoted between the said disks; a guide cylinder at the front of the pair of disks; a guide cylinder at the back of the 25 pair of disks; each guide cylinder comprising a fixed portion and a central rotary portion coupled with the said disks; and tumblers cooperating with the fixed and rotary portions of the said guide cylinders and 30 adapted to prevent the movement of the rotary portions and the turnable disks except when operated by a proper key.

In testimony whereof I have signed my name to this specification.

MAX HACKLÄNDER.
